UNITED STATES PATENT OFFICE.

FRANKLIN STRATTON, OF BUFFALO, NEW YORK, ASSIGNOR TO THE STRATTON ROTATING ENGINE COMPANY, OF BUFFALO, NEW YORK, A CORPORATION OF ARIZONA TERRITORY.

ROTATING ENGINE.

No. 869,032.

Specification of Letters Patent.

Patented Oct. 22, 1907.

Application filed December 6, 1906. Serial No. 346,597.

To all whom it may concern:

Be it known that I, FRANKLIN STRATTON, a citizen of the United States, residing at Buffalo, in the county of Erie and State of New York, have invented certain new and useful Improvements in Rotating Engines, of which the following is a specification.

This invention relates to rotating engines, such as are driven by steam, air, or other fluid agents, and which may be used as a pump when power is applied thereto. 10 The primary object of my invention is the production of an engine of the rotating type which is particularly adapted for use in a traction-wheel and forms part thereof, and which serves to revolve said wheel.

Another object is to provide an engine which can be 15 easily converted into a pump, by replacing the center valve with a similarly constructed valve having larger ports so as to increase the capacity and effectiveness of its pumping-action.

Another object is to provide an engine in which 20 vibration and friction are reduced to a minimum, and in which dead-centers are dispensed with.

Still further objects are, the production of an engine which is economical in the use of the motive-power, compact and simple in construction, easily reversible, 25 accessible to all parts, and well balanced, and also to improve the details of construction and operation so as to produce points of advantage which will be amplified as they occur hereinafter.

With these and other objects in view, I have illustrated my invention in a representative way, the mechanical elements used in combination in preferred form, being those now thought to be best adapted under the principle involved, in order to obtain the highest efficiency; and as I do not only claim the combination 30 of mechanical elements herein shown and described, but claim the essential elements in any arrangement and construction adapted for use under the principle involved, it is to be understood that this invention can be embodied in various ways, which will be readily understood by those skilled in the art.

In the accompanying drawings, my invention is illustrated for use as a steam-engine, but I do not wish to limit myself to such use, since air, gas or any other vapors may be used in propelling the engine; and if desired, power may be applied to adapt the same for use 45 as a pump.

The invention consists in a plurality of rotating piston-cylinders constituting a spider and having pistons reciprocal therein, an inlet and an exhaust for the motive power common to all cylinders, a fixed track or 50 guide, and devices connected with the pistons to cause the spider to rotate when the motive power acts upon the pistons.

My invention further consists in the construction, arrangement and combination of elements or parts to be 55 hereinafter described and particularly pointed out in the appended claims.

In the drawings,—Figure 1 is a side elevation of a traction-wheel showing my invention embodied therein, part of a running gear of a vehicle being shown in 60 connection therewith. Fig. 2 is a side elevation of my improved engine showing the same adapted for stationary use. Fig. 3 is a front elevation of the same. Fig. 4 is a front elevation showing the engine inclosed within a casing, the lower portion of which is shown in 65 section. Fig. 5 is a vertical section taken just outside of the spider and its rollers and through one cam. Fig. 6 is a vertical section taken through the center of all the cylinders. Fig. 7 is a vertical section taken at right angles to the plane of Fig. 6. Figs. 8 and 9 are partial 70 sections in the same plane as that of Fig. 6. Figs. 10 and 11 are side elevations of the spider viewed from opposite sides. Fig. 12 is an edge view and Fig. 13 a vertical section through the spider and its trunnion. Fig. 14 is a perspective detail of the trunnion. Fig. 15 75 is a vertical section through the casing. Fig. 16 is a section through Fig. 15 on the line 16—16. Fig. 17 is an enlarged sectional detail showing the catch in the casing. Figs. 18 and 19 are side and edge views of the link mechanisms for connecting the pistons in pairs. 80 Fig. 20 is a disconnected edge view of one of the link-members of one of the link-mechanisms. Fig. 21 is a plan view of the device shown in Fig. 18. Fig. 22 is a section on the line 22—22 of Fig. 2. Fig. 23 is a perspective detail of the cam. Fig. 24 is a side elevation 85 of the same. Fig. 25 is a perspective detail of the regulating-valve.

Referring to the drawings in detail, corresponding numerals of reference refer to corresponding parts in the several figures.

Reference being had to Fig. 1, the numeral 1 designates the running-gear of a vehicle, and 2 a traction-wheel journaled to revolve in said running-gear. Wheel 2 comprises the wheel-felly 3 having suitable tires 4 and inwardly directed lugs 5 to which are connected lugs 6 extending from the engine, designated 7, which serves as the hub of the wheel.

When used as a stationary engine, standards 8 are provided, as shown in Figs. 2 to 7, in which the engine is supported. It is apparent that the running-gear 100 shown in Fig. 1 or the standards just referred to, must serve to support the engine and both carry boxes 9 which support the hollow hubs 10 of two cams or roller guides 11 (see Figs. 7 and 23), which hubs form the bearing for a hollow trunnion 12 on which the revolving spider or cylinder-body 13 is supported. Said

spider or cylinder-body is preferably cast in the shape best shown in Figs. 10, 11 and 12, with details of construction which will be described below; and transversely through its thickened hub is drilled an axial 5 hole having radial recesses 14 in one end of the hub and an annular recess 15 in the other end. The trunnion is preferably of tool steel, and is forced tightly into this hole. It has exterior wings 16 which fit into the radial recesses 14, and exterior threads 17 at a proper 10 point on its body so that when the wings fit accurately into the recesses, a collar 18 can be screwed onto the thread and into the annular recess 15, thereby firmly and yet removably centering the trunnion within the casting and affording a steel shaft upon which the 15 whole can revolve within the hollow hubs of the cams. This I consider an important feature of my invention, because it simplifies and cheapens the construction, permits the wearing parts to be made of steel, and also utilizes steel for those parts which must be accurately 20 made or provided with ports.

The spider 13 contains four radial cylinders 20 notched at their outer ends, as at 21, and within these cylinders are located properly packed pistons 22 having outwardly projecting piston-rods 23. At the outer ends 25 of the latter are cross-heads 24 projecting through said notches 21 and connected in diametric pairs, as best seen in Figs. 5, 18 and 19. Each end of each cross-head carries an inwardly and laterally curved arm 25 (all the arms curving in one direction from the piston- 30 rods), and between the inner ends of each pair of arms is supported a box 26 having an opening which slides 35 on a guide rod 27. The latter is preferably square and of steel, and its reduced inner end is stepped in a socket 28 in the spider near the hub of the latter, its body standing parallel with the adjacent cylinder, and its 40 reduced outer end is held in place by a nut 29 screwed into a threaded opening in the spider—see Fig. 6. This view shows the box 26 as a single member having an opening through it for the guide-rod; but in Figs. 18 45 to 22 half the opening is formed in the outer face of the box and a plate 30 is screwed or bolted to the box and forms the other half of the opening—thus permitting the replacing of parts which may become worn. I consider the removability of the guide rods 27 an important 50 feature of my invention, because they can readily be removed or replaced by taking off the casing described below, unscrewing the nuts 29, and withdrawing the rods bodily. Also, any one of the boxes can then be removed without disconnecting other parts of the machine than those attached to it.

Links 32 connect opposite boxes in pairs, there being preferably two of these links on each side of the spider. In Fig. 5 the two upright links are shown moving astride the trunnion and behind the cam, and it will be understood that the other two links, which at this time stand horizontal, connect the other two boxes on the other side of the spider—hence one pair of links does not interfere with the operation of the other. By preference each link takes through an ear 33 formed on one box, in which it is adjustable between nuts 34 on either side of the ear; while the opposite end of the link is integral with the opposite box 26 in which one of two stub shafts 36 is journaled to revolve. If desired the links may be separate and provided with eyes 65 through which said stub shafts may project. On said

stub shafts are journaled rollers 37 which travel on the active faces of the cams 11. I have described and shown stub shafts and rollers on both sides of each box, and cams at both sides of the machine; but it is possible that one cam and one set of rollers could be omitted entirely, although I prefer the construction shown because it prevents the cramping of the boxes on the guide-rods. 70

The casing which incloses the spider is best shown in Figs. 4, 15, and 16, and is indicated in dotted lines in Fig. 2. It comprises an annular rim section 40 having internally projecting lugs 41 adapted to be bolted to the lugs 6 on the spider 13 of the engine; two end plates 43 whose peripheries fit the axial ends of said section and whose centers have openings 44 of sufficient size to 80 loosely inclose the hubs of the cams; and bayonet-joints 45 by which the end plates are connected with the interposed rim section. In assembling the parts, after the bayonet-joint elements have been connected, a catch (best shown in Fig. 17), may be employed to prevent 85 them from becoming disconnected. This consists of a stud 46 projecting inward from the rim section, and a spring-pressed bolt 47 carried by the end plate and whose tip engages behind the stud after the end plate has been turned so that the bayonet-joint members are 90 engaged. I consider this an important feature of my invention, because it permits the ready removal of the casing when access to the interior mechanism is desired; it holds the part of the casing in place against all ordinary vibration; and it provides a catch and a bayonet-joint which do so hold the parts connected and which permit their instantaneous disconnection when required. 95

The regulating-valve, best shown in Figs. 6, 7, and 25 is a tubular member exteriorly shaped to fit the interior of the trunnion 12. The latter (Figs. 7 and 13) is formed with a large bore 48 at its outlet end, a smaller bore 49 at its inlet end, and an intermediate tapered-portion 50 through which are cut four radial ports 51, the extremities of the trunnion being internally threaded for the reception of the nipples 52 and packing to make a tight joint around the tubular valve, designated 53. It will be understood that the latter is normally stationary while the trunnion revolves. The valve 53 has at its larger end a thread 54 for receiving nuts 55, 100 between which and the nipple 51 there are ball-bearings 56; and it has at its smaller end similar threads 540 for nuts 550 which adjust ball-bearings 560 against the nipple at the other end of the trunnion; an adjusting-gear 60 being here interposed as described below. At 105 opposite ends of the valve are stuffing-boxes 57, one connected with the inlet 58 and the other with the outlet 59 so as to permit the valve to rotate while the inlet and outlet remain stationary. Gear 60, fixed on the valve as above mentioned, is engaged by a sector 61 110 having a handle 62, and the sector is pivoted on a pin 63 projecting from the forward standards on the stationary engine, and from the running gear in the application of the engine shown in Fig. 1; the construction being such that when the handle is moved, the sector 115 will turn the gear and the valve. Within its tapered portion the latter is provided with an oblique partition 64, on opposite sides of which are the inlet port 65 and the outlet port 66, both arranged so that they register with the port 51 in the trunnion 12 than which they are 120

125 130

of greater length so that the valve may be adjusted longitudinally within the trunnion to take up wear between these parts. I consider this an important detail of my invention, because it permits the adjustment 5 of the valve to take up wear or its longitudinal removal for repair or substitution both without disconnecting other parts of the machine. The valve may well be made of tool steel to prevent its rapidly wearing away, and if the size and the shape of parts therein are to be 10 changed, it can be done by removing the valve only. Moreover, as described below the manipulation of a single lever which oscillates this valve within the trunnion is sufficient to start or stop the engine, to drive it forward or backward, and to drive it at variable 15 speeds; and this also I consider an important feature of the invention.

In operation, the steam is admitted through a cock (not shown) and let into the inlet 58, whence it flows through the valve and by the partition therein is directed out through the port 65. If the valve is set as 20 shown in Fig. 6 so that this port is directed toward the shortest diameter of the cams, the engine will stand at rest; but by turning the valve in either direction while the cams remain stationary, the engine will be caused 25 to rotate in that direction and at a speed proportionate to the degree to which the valve is turned; hence the manipulation of a single handle such as that numbered 62, will start or stop the engine, will drive it in either direction, and will control the speed. In Figs. 8 and 30 9 the valve is shown as turned with respect to the cams. The result is that the inflowing steam passes out the inlet port 65, and through one of the ports 51 in the trunnion when that port registers with the inlet port 65. Entering the cylinder, it moves the piston outward, and through the links this piston causes the opposite piston to move inward, while the exhaust steam in the opposite cylinder passes through the opposite port 51 in the trunnion, through the outlet port 66 in the valve, and out the exhaust 59. Because the outlet 35 end of the valve is made of larger diameter than the inlet end, the exhausting steam has a chance for expansion without retarding the rotation of the engine. As the opposite pistons move as just described, their rollers impinge against the active faces of the cams and 40 45 produce the rotation of the spider in a manner which will be clear, the direction of rotation depending upon the direction in which the valve has been turned, and the speed of rotation depending upon the degree to which the valve has been turned. It will be clear that 50 55 by setting the cams upon the trunnion, the proper lead can be secured so that the engine will take in its live steam and exhaust its dead steam at points which will secure the highest efficiency of action.

At diametrically opposite points, or approximately 55 so, the active face of each cam is concentric with respect to the trunnion of the spider on which it is mounted, said concentric portions being in arcs of circles of different diameters and serve to cause a momentary cessation of movement of the pistons. These 60 centric portions are connected by eccentric or cam portions which cause the pistons to travel within the cylinders when the rollers ride over the latter. The cams are so affixed to the support that when the rollers ride over their concentric portions, opposite pistons 65 are at their outer and inner limits of travel, respec-

tively. This provides for the free escape of the fluid-agent from the exhaust and consequently assures free action and high efficiency.

Having thus described my invention, what I claim is,—

1. In an engine or the like, the combination with a rotating element having a plurality of radially disposed cylinders of a valve around which said rotating element rotates, a piston reciprocal in each cylinder, a fixed guide, and connections between opposite pistons and between the 70 pistons and said guide.

2. In an engine or the like, the combination with a plurality of radially disposed rotating piston-cylinders, of a valve around which said cylinders rotate, a piston reciprocal in each cylinder, a fixed guide, and link-mechanism 75 having connection with opposite pistons and being guided on said guides.

3. In an engine or the like, the combination with a plurality of rotating piston-cylinders, of a valve around which the cylinders rotate, a piston reciprocal in each cylinder and having a piston-rod, means for connecting the pistons in pairs, and a fixed cam or guide over which said connecting-means travel to govern the movement of the pistons and the rotation of the cylinders.

4. In an engine, the combination with a spider having 90 a plurality of radially disposed piston-cylinders, of a wheel-rim connected to said spider, a valve controlling the admission of the fluid-agent to and the exhaust thereof from said cylinders, a piston reciprocal in each cylinder, fixed guiding-means, and connections with the pistons 95 traveling around said guiding-means and governing the movements of the piston and the rotation of the spider.

5. The combination with a support, of a hollow valve having an inlet-port and an exhaust-port, a fixed cam or guide held on said support, a spider rotatable on said 100 valve and having radially disposed cylinders with ports at their inner ends for the admission and exhaust of the fluid-agent, pistons connected in tandem and reciprocal within the cylinders, and means on the connections of said pistons co-acting with said cam or guide to govern the movement of the pistons and the rotation of the spider.

6. In a rotating-engine, the combination with a support, of a hollow-valve having an inlet and an exhaust, a spider rotatable around said valve and having a plurality of cylinders and a hollow trunnion extending from opposite 110 sides thereof, a fixed cam or guide on each side of the spider through which said hollow shaft extends, pistons reciprocal in said cylinders, connections, to said pistons guided on said cam or guide, and means for adjusting the valve to position the inlet thereof in line with the 115 vertical center of the engine or to either sides of the vertical center, for the purpose described.

7. In a rotating-engine, the combination with a support, of a hollow-valve having an inlet and an exhaust, a spider rotatable around said valve and having a plurality of cylinders and a hollow trunnion extending from opposite sides thereof, a fixed cam or guide on each side of the spider through which said trunnion extends, pistons reciprocal in said cylinders, link-mechanisms connecting the pistons in tandem and having rollers adapted to travel 120 on said cam or guide, and means for oscillating the valve within said spider to regulate the speed thereof, to govern the direction of rotation of said spider, and to stop the engine.

8. In a rotating engine, the combination of a spider having radially disposed cylinders, a hollow center valve having its axis coincident with the axis of said spider, a fixed cam, pistons reciprocal in said cylinders, mechanism connecting the pistons in pairs and having rollers riding around said cam or guide, and means for guiding said 130 mechanism on the spider.

9. In a rotating engine, the combination of a spider having piston-cylinders connected by webs and a hollow trunnion extending from opposite sides of said spider, a tubular valve within said shaft and arranged to admit the fluid-agent to and exhaust the same from the cylinders, fixed cams on opposite sides of the spider through which said hollow trunnion passes, pistons reciprocal in said cylinders, a link-mechanism on each side of the spider connecting co- 140

- incident pistons and having a roller adapted to travel around said cam, and guides on said spider for guiding the link-mechanisms.
10. In a rotating engine, the combination of a rotating spider having radially disposed cylinders and a center hollow trunnion tapered internally at a point between the cylinders to provide a tapered valve-seat, a hollow-valve in said trunnion having a correspondingly tapered portion fitting the valve-seat and having also an inlet-port and an exhaust-port, means for moving the valve lengthwise, means for rotating said valve, a fixed cam or guide, pistons reciprocal in said cylinders, and connections to the pistons adapted to travel around said cam or guide.
11. In a rotating-engine, the combination of a rotating spider having a center bore and a plurality of radially disposed cylinders, a guide-rod parallel with each cylinder, a hollow valve in the bore of the spider having an inlet-port and an exhaust-port, a fixed cam or guide on each side of the spider, pistons reciprocal in the cylinders, mechanism connecting the pistons in pairs and having boxes fitting said guide-rods, a shaft in each box, and rollers on said shaft adapted to travel around said cams or guides.
12. In a rotating-engine, the combination of a rotating spider having a center bore and a plurality of radially disposed cylinders connected by webs, a hollow valve in the bore of the spider having an inlet-port and an exhaust-port, a fixed cam or guide on each side of the spider, a guide-rod parallel with each cylinder and removably secured to the spider, pistons reciprocal in the cylinders, and mechanism connecting the pistons in pairs and having boxes fitting said guide-rods, a shaft in each of said boxes, rollers on said shafts adapted to travel around said cams or guides, a gear affixed to the hollow-valve, and a handle having a segment-gear in mesh with the gear of the valve.
13. In a rotating-engine, the combination with a spider having a center-bore and radially disposed cylinders, a hollow-valve in said bore having an inlet-port and an exhaust-port, means for rotating said valve, a fixed cam or guide, pistons reciprocal in said cylinders and each having a piston-rod, link-connections on the outside of the spider having each connection with the piston-rods of opposite pistons, and rollers carried on said link-connections and adapted to travel around said cam or guide.
14. In a rotating-engine, the combination with a spider of cast metal having cylinders therein and a central axial hole therethrough, pistons in said cylinders, and means for driving them by the fluid-agent; of a steel trunnion fitting tightly into said hole, means for holding the trunnion within the spider, and ports for the admission and exhaust of the fluid-agent.
15. In a rotating-engine, the combination with a spider of cast metal having cylinders therein and a central axial hole therethrough, thickened hubs around said hole, one hub having radial recesses in its outer end and the other having an annular recess in its outer end, pistons in said cylinders, and means for driving them by the fluid-agent; of a steel trunnion fitting tightly into said hole and having wings adapted to engage said radial recesses and an exterior screw-thread at a proper point, a collar on said thread adapted to enter said annular recess, and ports for the admission and exhaust of the fluid-agent.
16. In a rotating-engine, the combination with a spider having radial cylinders, pistons and piston-rods therein, and a trunnion and valve for admitting and exhausting the fluid agent to and from said cylinders; of guide-rods supported in the spider parallel with the cylinders, boxes moving on the guide-rods, and connections between the boxes and piston-rods.
17. In a rotating-engine, the combination with a spider having cylinders, pistons and piston-rods therein, and a trunnion and valve for admitting and exhausting the fluid agent to and from said cylinders; of guide-rods parallel with the cylinders, sockets in the spider in which the inner ends of said rods are stepped, nuts in the spider by which the outer ends of said rods are supported, boxes moving on the guide-rods, and connections between the boxes and piston-rods.
18. In a rotating-engine, the combination with a spider having radial cylinders, pistons and piston-rods therein,
- and a trunnion and valve for admitting the fluid-agent to and from said cylinders; of guide-rods supported in the spider parallel with the cylinders, boxes connected with the piston-rods and having partial openings moving on the guide rods, and plates detachably connected with the boxes and having complementary openings moving on said guide-rods.
19. In a rotating-engine, the combination with a spider having four cylinders, pistons and piston-rods therein, cross-heads on said rods, and boxes connected with the cross-heads; of links connecting the opposite boxes in pairs, the links which connect one pair of boxes being on one side of the spider opposite from those which connect the other pair of boxes, and a valve for the admission and exhaust of the fluid-agent to and from said cylinders.
20. In a rotating engine, the combination with a spider having four cylinders, pistons and piston-rods therein, and boxes connected with said rods; of a trunnion on which the spider rotates, a valve therein for the admission and exhaust of the fluid-agent to and from said cylinders, and links connecting the opposite boxes in pairs, the links which connect one pair of boxes being on one side of the spider opposite from those which connect the other pair of boxes.
21. In a rotating engine, the combination with a spider having four cylinders, pistons and piston-rods therein, and boxes connected with said rods, of a trunnion on which the spider rotates, a valve therein for the admission and exhaust of the fluid-agent to and from said cylinders, and links connecting the opposite boxes in pairs, the links which connect one pair of boxes being opposite from those which connect the other pair of boxes, fixed cams in which the trunnion rotates, and rollers on the boxes travelling on the active faces of said cams, each pair of links standing astride said trunnion.
22. In a rotating engine, the combination with a spider having four cylinders, pistons and piston-rods therein, and boxes connected with said rods, each box having stub shafts at one side of the piston-rod and an ear at the other side; of a trunnion on which the spider is secured, a valve therein for admitting and exhausting the fluid-agent, non-rotary cams on said trunnion, rollers secured on the stub shaft and traveling on the active faces of the cams, and a link connecting each box with the ear on the box diametrically opposite.
23. In a rotating-engine, the combination with a spider having four cylinders, pistons and piston-rods therein, and boxes connected with said rods, each box having stub shafts at one side of the piston rod and an ear at the other side; of a trunnion on which the spider is secured, a valve therein for admitting and exhausting the fluid-agent, non-rotary cams on said trunnion, rollers journaled on the boxes and traveling on the active faces of the cams, and a link connecting each box with the ear on the box diametrically opposite, each link passing to one side of said trunnion and being threaded where it extends through the ear, and nuts on the threaded portion at each side of the ear, for the purpose set forth.
24. In a rotating-engine, the combination with a rotary spider and its cylinders and pistons, a valve for admitting the fluid-agent to and exhausting it from said cylinders, and cams with which said pistons co-act; of a casing comprising a rim member attached to the spider, and end plates detachably connected with the rim member and having openings surrounding the hubs of said cams.
25. In a rotating-engine, the combination with a rotary spider and its cylinders and pistons, a valve for admitting the fluid-agent to and exhausting it from said cylinders, and cams with which said pistons co-act; of a casing comprising a rim member surrounding the spider, end plates having openings surrounding the hubs of the cams, and bayonet-joints detachably connecting said plates and rim-member.
26. In a rotating-engine, the combination with a rotary spider and its cylinders and pistons, a valve for admitting the fluid-agent to and exhausting it from said cylinders, and cams with which said pistons co-act; of a casing comprising a rim member surrounding the spider, end plates having openings surrounding the hubs of the cams, detachable connections between said end plates and rim-member.

member, and catches for holding those parts together after the connections are engaged.

27. In a rotating-engine, the combination with a spider having cylinders, pistons therein, rollers connected with the pistons, and fixed cams whose active faces engage said rollers; of a trunnion journaled in said cams and fast in the spider and having ports communicating with its cylinders, a tubular valve within the trunnion and having inlet and outlet ports adapted to register with those in said trunnion, a partition between said inlet and outlet ports, and means for setting the valve with respect to the positions of the cams.

28. In a rotating-engine, the combination with a spider having cylinders, pistons therein, rollers connected with the pistons, and fixed cams whose active faces engage said rollers; of a trunnion journaled in said cams and fast in the spider and having ports communicating with its cylinders, a tubular valve within the trunnion and having inlet and outlet ports adapted to register with those in said trunnion, a partition between said inlet and outlet ports, and means for setting the valve with respect to the positions of the cams.

29. In a rotating-engine, the combination with a spider having cylinders, pistons therein, rollers connected with the pistons, and fixed cams whose active faces engage said rollers; of a trunnion journaled in said cams and fast in the spider and having ports communicating with

its cylinders, a tubular valve within the trunnion and having inlet and outlet ports adapted to register with those in said trunnion, a partition between said inlet and outlet ports, nipples on the trunnion, nuts on the valve, ball-bearings interposed between the nipples and nuts, an inlet and an outlet connected with opposite ends of said valve, and means for setting the latter with respect to the position of the cams.

30. In a rotating engine, the combination with a spider having cylinders, pistons therein, rollers connected with the pistons, cams engaging said rollers, and a tubular trunnion fixed through the spider and journaled in the cams, the bore of the trunnion being tapered where it passes through the spider and there provided with ports leading into said cylinders; of a tubular valve located within the trunnion and having a tapered portion fitting the similar portion of the trunnion and provided with opposite inlet and outlet ports, an oblique partition between said ports, means for setting the valve with respect to the position of the cams, and nuts beyond the ends of the trunnion, as and for the purpose set forth.

In testimony whereof, I have affixed my signature in the presence of two subscribing witnesses.

FRANKLIN STRATTON.
